UNITED STATES PATENT OFFICE.

WILLIAM CALDWELL HUNTINGTON, OF HINSDALE, ILLINOIS.

PROJECTILE.

1,198,035.

Specification of Letters Patent. Patented Sept. 12, 1916.

Application filed December 14, 1915. Serial No. 66,711.

To all whom it may concern:

Be it known that I, WILLIAM CALDWELL HUNTINGTON, a citizen of the United States, residing at Hinsdale, in the county of Du-
page and State of Illinois, have invented
5 new and useful Improvements in Projectiles, of which the following is a full, clear, and exact description.

10 My invention relates to projectiles both for ordnance and smaller fire arms, and particularly anti-air-craft projectiles.

15 The objects of my invention are, primarily, to provide a projectile that contains a number of independent parts which are tied together, and which, when the projectile is discharged from the gun or cannon, separate the length of the wires, chains or other flexible sinuate means connecting them and thus cover a comparatively large
20 area and enables the said parts to tear and break the planes the frame and stays of the air-craft it may strike, so badly, as to incapacitate it for further flight. This I accomplish by the means hereinafter described, and as particularly pointed out in
25 the claims.

30 In the drawings: Figure 1 is a side view of the projectile embodying my improvements partially inclosed by its casing which is shown in section. Fig. 2 is a transverse section thereof taken on dotted line 2—2, Fig. 1. Fig. 3 is a diagrammatical view of said projectile as it appears when describing its trajectory. Figs. 4, 5 and 6 are, respectively, views similar to Figs. 1, 2 and 3 showing a modified form of my invention. Figs. 7, 8, and 9 are, respectively, views similar to Figs. 1, 2 and 3 showing another modified form of my invention. Figs. 10,
35 11 and 12 are, respectively, views similar to Figs. 1, 2 and 3 showing yet another modification of my invention. Figs. 13, 14 and 15 are, respectively, also views similar to Figs. 1, 2 and 3, illustrating a fourth modification of my invention. Figs. 16, 17 and 18 are, respectively, views similar to Figs. 1, 2 and 3 of a fifth modification of my invention.

40 The preferred form of my invention, shown in the first three figures of the drawings, comprises a substantially cylindrical shell having a conical head and having the diameter of its base reduced. The outer surface of this reduced portion is slightly
45 tapered from the shoulder *a* resulting from this reduction to the rear end of the projec-

tile. The projectile, as thus described, consists of, preferably, an even number of sections *B* that are made by dividing the same longitudinally and transaxially, and said sections correspond in longitudinal and transverse contours, and are, therefore, pointed at one end and provided with a reduced shank *b* at the other. Each of these shanks has one end of a flexible sinuate 60 tether or connecting element *C*, such as a cable or wire or chain, secured, preferably, to the outer curved surface thereof near the shoulder *a*. These tethers are, preferably, all of the same length and have their other 65 ends securely fastened to a circular anchor-plate or diaphragm *c* near the outer circumference thereof at equal distances apart, and between said diaphragm and their opposite ends said tethers are wound around said 70 shanks when the sections are in their assembled position.

75 The assembled section may be tied together in any suitable manner, but I prefer to keep them in their relative positions until 80 fired from the gun or cannon by a cylindrical casing *D* of brass or other suitable material, the upper portion of which incloses the cylindrical portion of the shell. The base *d* of this casing is closed and the 85 upper side thereof is bored to provide a chamber *E* which is filled with a suitable explosive, and a time fuse *F* is tapped through the center of said base into chamber *E*.

90 When the shell is properly placed in its casing diaphragm *c* is seated on base *d* and covers over and closes chamber *E*, and the shanks of the sections of the projectile and the tethers occupy the space between the diaphragm and shoulder *a* of the same. 95

95 When the projectile, hereinbefore described, is fired from a cannon, it will continue on its flight until the fuse *F* ignites the explosive in chamber *E*, whereupon it explodes and the sections of the projectile 100 separate and fly apart as they continue at an accelerated speed toward the air-craft (say) at which they were aimed and, particularly if the cannon was rifled, will revolve about the diaphragm, and cover an 105 area twice the length of the tethers and should they strike the object tear and break the parts of said air-craft so badly that further flight thereof is impossible.

110 In Figs. 4, 5 and 6, I show a modified construction of my invention in which the diaphragm is eliminated, and in which the

tethers 14 have their ends farthest from the shanks of the sections 15, 15 securely fastened to a ball 16 much less in diameter than the casing 17. The sections 15 of this modification are secured in casing 17 by pressing the upper edges of the latter into a suitable circumferential groove made in the base of the assembled projectile, and the casing below the projectile is filled with a suitable explosive 18.

In Figs. 7, 8 and 9, I show another modification of my improvements in which, instead of one projectile divided into sections, I employ seven, or any other suitable number of smaller solid bullet shaped projectiles 19, 19. These bullets are securely held in the upper part of a casing 20, similar to that shown in Figs. 1 and 2 of the drawings, and the tethers 21 are secured to the points of said bullets and from thence pass down between the same to the space below the same and above the diaphragm 22 where they are coiled lengthwise the casing and have their lower ends secured equi-distant apart to the diaphragm. The explosive is contained in a chamber covered over by said diaphragm, and a suitable fuse penetrates through the bottom of this chamber in the same manner as shown in Figs. 1, 2 and 3 of the drawings. In order to provide a point for this modified projectile, I have provided a cap 23 of the same shape as the head of the assembled projectile shown in said Figs. 1, 2 and 3, which fits over the upper end of the casing and has its edge lapped over and secured to the upper edge of the same.

In Figs. 10, 11 and 12, I illustrate yet another modification of my improved projectile which is similar in every respect to that shown in Figs. 7, 8 and 9 except that the bullets 24 have shanks 25 depending therefrom concentrically to their axes and the tethers 26 thereof have one end connected to the upper portions of said shanks 25 and then are wound each around the shank to which it is attached and have their opposite ends bunched and tied securely together in any suitable manner, independently of the diaphragm.

In Figs. 13, 14 and 15 of the drawings, I show a modification which differs from that shown in said Figs. 10, 11 and 12 only in the shape of the bullets 27, 27. These bullets are pointed at both ends and their tethers 28 are attached to their lower points and are loosely coiled in the space between the bullets and above the diaphragm, and have their lower ends suitably connected together.

Figs. 16, 17 and 18 of the drawings show a modification of my invention similar to that shown in Figs. 1, 2 and 3 thereof, except that the projectile is divided longitudinally into only two sections 29, 29, which do not have shanks, and the wire is wound

directly around the bodies of said sections. The tethering wires 30, 30 of this modification have their ends opposite those attached to said sections tied together; the diaphragm 31 is not seated upon the base, but simply separates the lower portion of the bore of the casing 23 in which the explosive 33 is contained from the upper portion of the same, and the casing is provided with a cap 34 similar to that shown in Figs. 7, 8 and 9 of the drawings.

It will be understood that in the manufacture of my invention, I will utilize all the means for improving the same that have been developed by recent advances in the science of ordnance and projectiles to which my invention belongs. All such changes as may be required in order to enable me to do this, I desire to be understood as coming within the scope of my invention.

What I claim as new is:

1. In combination, a projectile divided longitudinally in sections, and flexible means which by being wound around the projectile hold the sections together normally and also form connecting members between the sections after said sections have separated.

2. In combination, a projectile divided longitudinally into separable sections having their rear ends reduced, and means wound upon the exterior of said reduced ends to bind said sections together when assembled and to connect said sections when separated.

3. In combination, a projectile divided into a number of equal sections, the rear ends of which are reduced in diameter, flexible means for connecting the same together, and a cylindrical shell in which the base of said projectile and said connecting means are retained.

4. In combination, a projectile the rear end of which is reduced in diameter and is divided longitudinally into sections, flexible sinuate means of equal length for connecting said sections together, and a shell within which the base of said projectile and said sinuate connecting means are retained.

5. In combination, a projectile comprising a number of corresponding parts nested around the axis thereof, flexible sinuate means for connecting said parts, a common element distinct from the parts of the projectile to which said sinuate means are connected, and a shell in which the base of said parts, said sinuate means and said common element are inclosed.

6. In combination, a projectile divided longitudinally and centrally into a suitable number of corresponding sections nested around a common axis, and flexible sinuate means coiled around the ends of and connecting different sections.

7. In combination, a projectile divided longitudinally into a suitable number of corresponding sections, each having a shank of transversely reduced dimensions, and flexible sinuate tethers the ends of which are connected to said shanks, and between their ends are coiled upon said shanks.
8. In combination, a projectile divided longitudinally and centrally into a suitable number of corresponding sections each having a shank of reduced transverse dimensions, flexible sinuate tethers the ends of

which are connected to said sections, and a common coupling element to which said tethers are connected and between which and the ends thereof said tethers are coiled about said shanks.

In witness whereof I have hereunto set my hand this 11th day of December, 1915.

WILLIAM CALDWELL HUNTINGTON.
